UNITED STATES PATENT OFFICE.

GEORGE R. McDONALD, OF BROOKLYN, NEW YORK.

ILLUMINATED SIGN FOR CONVEYANCES.

Application filed June 16, 1922. Serial No. 568,857.

To all whom it may concern:

Be it known that I, GEORGE R. McDONALD, citizen of the United States, residing at Brooklyn, city and State of New York, 5 Kings County, have invented certain new and useful Improvements in Illuminated Signs for Conveyances, of which the following is a specification.

This invention relates to signs and more 10 particularly those applied to conveyances as motor-vehicles, motor-boats and aerial machinery where it is necessary to designate conveyances by number for identification.

The object of the invention is to provide 15 a sign, every character of which will be instantly visible so it can be read before the conveyance is beyond the range of vision; a further object is to provide a suitable bracket and support for the sign upon 20 the conveyance; a further object is to provide means by which an ordinary sign may be supported upon an ordinary bracket in such a manner that it will be more quickly legible than the ordinary sign as heretofore 25 supported upon the conveyance, and a still further object is to provide means for supporting the sign in the manner described which is simple, and cheap of construction and which may be readily applied or removed. 30

Referring to the accompanying drawings forming a part of this specification, Fig. 1 is a plan view showing the bracket as applied to a conveyance, a portion of the 35 frame of which is shown in section, the lamp and sign being in position on the bracket; Fig. 2 is a front elevation showing the same parts and elements; Fig. 3 is a detail sectional view showing the manner of 40 constructing the sign, taken on the line iii—iii of Fig. 2; Fig. 4 is a plan view showing a modified form of the sign and Fig. 5 is a sectional view taken on the line iv—iv 45 of Fig. 4 with parts of the bracket broken away; Fig. 6 is a perspective view showing a modified form of the device; Fig. 7 is a plan view of the modified form showing the device applied to a short bracket; Fig. 8 is a diagrammatic view showing a further 50 modification of the device; Fig. 9 is a sectional view taken on the line 9—9 of Fig. 7 and Fig. 10 is a sectional view taken on the line 10—10 of Fig. 7.

In the drawings the numeral 10 designates the frame of a conveyance, 11 the supporting bracket, 12 screws securing the

bracket to the conveyance, 13, an arm extending laterally from the plate 14, and 15 a post adapted to receive a removable sign and lamp support 16. The post 15 has a 60 flattened surface 17 adapted for engagement by a set screw 18, to hold the support 16 upon the post and prevent it from turning relatively to the post.

The support 16 is of concave shape, being 65 constructed upon the radius of a circle, and resembling, as shown in Figs. 1, 2 and 3, a segment of a cylinder as at 19. At one end is an extension having the cylindrical opening 20 to admit the post 15, and also having 70 threaded boss 21, to admit the set-screw 18, and an apertured lug 22 to admit the threaded bolt 23 of the lamp 24, which is secured in position by the thumb-nut 25. The support is also provided with threaded openings 75 to admit set-screws 26 for holding the sign in position upon the support.

The sign itself consists, as shown in Figures 1, 2 and 3 of a concave plate, 27, constituting the segment of a cylinder having 80 preferably raised or embossed letters thereon, of a polished metal or enamel or other material which will reflect the light and the remainder of the plate or background being ground to a rough surface or of a dark color 85 so it will not reflect the light so perfectly, thus affording the greatest possible contrast between the characters and the background of the sign.

By experiment it has been found that 90 when the light is placed adjacent to the sign so constructed each part thereof owing to the laws of reflection, serves to condense the rays of light so that all parts of the sign are equally visible at the same time. The sign-plate has slotted apertures 28 to admit the 95 set-screws 26 which provide for lateral adjustment of the plate 27 relative to the support 16. In Figure 3 the characters are shown at an elevation, as 29 above the 100 ground 30.

The lamp may be of any suitable type and in the drawings the lamp 24 represents an ordinary tail-lamp having the projector 24^a for a red light, and the projector 24^b for a 105 clear light to illuminate the sign.

In Figs. 4 and 5 is shown a modified form of the device in which the support 16 and the sign-plate 27 are constructed to resemble a section of a hollow sphere, which serves to 110 concentrate the rays of light more fully thus insuring greater visibility.

The device as shown in the modified form in Fig. 6, embodies the bracket arm 31 of the ordinary type, the beveled bar 32, with the curved portion 33 and slots 34 for bolts 5 34^a. The sign-plate 35 is bent to conform to the curved surface of the bar 32 and the bolts 34^a are inserted through the slots 34 to secure the sign-plate in position. Wedge-shaped washers 37 are employed to equalize 10 compression of the bolts upon the plate. The lamp 38 is supported upon the arched support 39 and held in position by the bar 40 and bolts 34^a. A ruby lens 41 is provided in the front plate of the lamp, as 42 to provide 15 a danger signal. The lower portion of the lamp is open at 43 so that the light falls upon the sign which is inclined and curved so as to be more readily visible, thus insuring perfect visibility.

20 In Fig. 7 the bracket-bar 44 is shorter than in Fig. 6 and in this case the bar 45 extends beyond the end of the bracket. In Fig. 8 the bracket-bar 46 is shown in dotted lines, and the wedge-shaped sleeves 47, 48 25 and 49 are employed in place of the bar 45. The right-hand sleeve 47, left hand sleeve 48 and center 49, serve to give curvature to the sign-plate, also to maintain it in an inclined position. Any type of lamp may be used 30 with this sign.

While I have described and shown the particular forms of construction illustrated in the drawings, I do not wish to be limited thereby but reserve the right to depart 35 therefrom within the reasonable scope and spirit of the invention.

Having thus described my invention, what

I claim as new therein and desire to secure by Letters Patent of the United States, is:

1. In an illuminated sign for conveyances, 40 the arrangement and combination of a supporting rod serving as a bracket, means for securing said rod to a conveyance, a curved sign-tag adapted for being mounted on the bracket, supporting means held on the rod 45 having one surface adapted to rest against the flat surface of the rod, and an oppositely disposed surface adapted to fit the curved rear surface of the curved sign-tag and hold the sign in an inclined position, that light 50 from a lamp above the sign may be better reflected to the eye of an observer; means for securing the sign-tag to the bracket and means for supporting a light above the sign-tag as shown and described. 55

2. In an illuminated sign-tag for conveyances the arrangement and combination of a bracket, means for securing the bracket to a conveyance, a curved sign-tag, means for securing the curved sign-tag to the 60 bracket in an inclined position, means for supporting a lamp adjacent the curved sign-tag upon the conveyance so that the light may fall directly upon the sign-tag at a reflecting angle with the eye, substantially 65 as shown and described.

In testimony whereof, I GEORGE R. McDONALD have signed my name to this specification in the presence of two subscribing witnesses, this seventeenth day of May 1922. 70

GEORGE R. McDONALD.
